UNITED STATES PATENT OFFICE.

AUGUST SCHULZE, OF NEW YORK, N. Y., ASSIGNOR OF THREE-FOURTHS
TO SIGMUND LANGSDORF, OF SAME PLACE.

HAND-MIRROR HOLDER FOR TOILET-CASES.

SPECIFICATION forming part of Letters Patent No. 275,949, dated April 17, 1883.

Application filed March 2, 1883. (No model.)

To all whom it may concern:

Be it known that I, AUGUST SCHULZE, of the city, county, and State of New York, have invented a new and useful Improvement in 5 Hand-Mirror Holders, of which the following is a full, clear, and exact description.

Reference is to be had to the accompanying drawings, forming part of this specification, in which similar letters of reference indicate corresponding parts in all the figures.

Figure 1 is a perspective view of a toilet-case to which my improvement has been applied, shown open. Fig. 2 is a plan view of the mirror-holder. Fig. 3 is a sectional side 15 elevation of the same, taken through the line *x x*, Fig. 2. Fig. 4 is a sectional end elevation of the same, taken through the line *y y*, Fig. 3.

The object of this invention is to provide 20 hand-mirror holders constructed in such a manner as to adapt them to receive and hold securely hand-mirrors of various shapes and sizes.

The invention consists in a hand-mirror 25 holder constructed with a grooved block having a stationary recessed catch at one end, a plate sliding in the groove of the block, and having a recessed bar attached to it, and a spring attached to the block and the sliding 30 plate, whereby a hand-mirror will be securely held and can be readily put in and taken out, as will be hereinafter fully described.

A is the lower part, and B is the upper 35 part, of the toilet-case, which parts are hinged to each other, and are provided with a fastening in the ordinary manner.

To the inner side of the upper part or cover, B, of the toilet-case is secured a block, C, in the face of which is formed a dovetailed groove, 40 D, extending from one end of the block C nearly to its other end. Into the groove D is fitted a plate, E, which is made shorter than the said groove, so that it can slide longitudinally.

45 To the face of the outer end of the sliding

plate E is attached a cross-bar, F, the inner side of which is recessed or flanged to receive and hold the end of a mirror. To the other end of the block C is attached a stationary bar or catch, G, which is recessed upon its inner side to receive and hold the end of the mirror-handle. The middle part of the block C is slotted to receive a spring, H, of rubber, metal, or other suitable material. One end of the spring H is attached to the block C, and 50 its other end is attached to the sliding plate E, so that the said plate will be held inward by the tension of the spring H. With this construction the mirror is inserted in the holder by placing the end of the said mirror in the 55 recess of the holding-bar F and pushing the said bar F and the slide E outward, so that the end of the mirror-handle can be inserted in the recess of the stationary catch G, and the mirror will be held securely in place by 60 the tension of the spring H. The mirror is removed by pushing it forward until its handle can be raised from the catch G. With this 65 construction mirrors of various styles, shapes, and sizes can be held by the same holder, so 70 that it will no longer be necessary for the dealer to have cases made expressly for all the different shapes and sizes of mirrors.

The case is designed to be lined with satin or other suitable material in the ordinary manner, as shown in Fig. 1, so that the holder will 75 be wholly concealed.

Having thus described my invention, I claim as new and desire to secure by Letters Patent—

A hand-mirror holder made substantially as 80 herein shown and described, and consisting of the grooved block C, having stationary recessed catch G, the sliding plate E, having recessed bar F, and the spring H, whereby a hand-mirror will be securely held and can be 85 readily put in and taken out, as set forth.

AUGUST SCHULZE.
